CLAIM

I claim the ornamental design for a pair of shoe outsoles, as shown and described.

DESCRIPTION

FIG. 1 is a perspective view of the left odd of a pair of shoe outsoles showing my new design; the right sole being a mirror image, and being removed for convenience of illustration; and the broken lines showing a shoe upper illustrating the portion of the design that forms no part of the claim; FIG. 2 is a bottom plan view thereof; FIG. 3 is a left side elevational view thereof; FIG. 4 is a right side elevational view thereof; FIG. 5 is a front elevational view thereof; and, FIG. 6 is a rear elevational view thereof.
